United States Patent Office.

JAMES HAMMOND, OF ADAMS CENTRE, NEW YORK.

Letters Patent No. 69,660, dated October 8, 1867.

IMPROVEMENT IN CHIMNEY-CAPS.

The Schedule referred to in these Letters Patent and making part of the same.

TO ALL WHOM IT MAY CONCERN:

Be it known that I, JAMES HAMMOND, of Adams Centre, in the county of Jefferson, and State of New York, have invented a new and improved Chimney-Cap; and I do hereby declare that the following is a full, clear, and exact description thereof, which will enable others skilled in the art to make and use the same, reference being had to the accompanying drawings, forming part of this specification.

The present invention relates to a cap for chimneys, which is so constructed as to act as a preserver of chimneys, in completely preventing the rain from entering the top, while at the same time a proper and sufficient draught is obtained or admissible. In the accompanying plate of drawings my improved chimney-cap is illustrated—

Figure 1 being a plan or top view of its under side, and

Figure 2 a longitudinal vertical section of the same, in the plane of the line $z z$, fig. 1.

Similar letters of reference indicate corresponding parts.

A, in the drawings, represents my improved cap for chimneys, which consists of a cast-iron or other suitable metal plate, hollowed out upon its under side, with outward flared end and side strips B. C, four legs to the cap-plate A upon its under side, by which legs the cap-plate is stood upon the top of the chimney for which it is intended, raising it sufficiently above the same to cause no hindrance to the draught.

By a cap-plate of the construction above described, not only the rain is prevented from entering the chimney and the wind from driving down, but the passage of sparks therefrom arrested, and the rain conveyed out at the gutters in a stream.

Having thus described my invention, what I claim as new, and desire to secure by Letters Patent, is—

The chimney-cap, constructed as described, of one piece of cast metal, hollowed out upon its under side B, and having the legs C, and with its ends and sides B flared outward, as herein shown and described.

JAMES HAMMOND.
